US00D557679S

(12) **United States Design Patent** (10) **Patent No.:** **US D557,679 S**
(45) **Date of Patent:** **** Dec. 18, 2007**

(54) **DIGITAL AUDIO RECORDING DEVICE**

(75) Inventors: **Fadhl Bey**, San Francisco, CA (US);
David Noppenberger, Baltimore, MD (US); **Kelly Kodama**, Alamo, CA (US);
John Haggis, San Jose, CA (US); **Alan Czeszynski**, Pleasanton, CA (US);
Arthur Cohen, Cupertino, CA (US);
Francis Lau, Fremont, CA (US)

(73) Assignee: **Aerielle Technologies, Inc.**, Mountain View, CA (US)

(**) Term: **14 Years**

(21) Appl. No.: **29/246,870**

(22) Filed: **May 17, 2006**

(51) **LOC (8) Cl.** **14-01**

(52) **U.S. Cl.** **D14/167**

(58) **Field of Classification Search** D14/171, D14/217, 198, 197, 196, 195, 194, 193, 188, D14/168, 167, 162, 156, 136, 135, 368, 165, D14/496; D13/168; D10/15; 455/350, 455/347, 344; 386/69, 18

(57) **CLAIM**

The ornamental design for a digital audio recording device, as shown and described.

DESCRIPTION

FIG. 1 is an upper right front perspective view of the digital audio recording device;

FIG. 2 is an upper right front perspective view;

FIG. 3 is a front elevational view;

FIG. 4 is a top plan view;

FIG. 5 is a left side elevational view, right side is mirror image thereof;

FIG. 6 is a bottom plan view; and,

FIG. 7 is a rear elevational view.

The broken lines shown in the drawings form no part of the claimed design.
